United States Patent Office.

D. K. BOSWELL, OF COLUMBUS, OHIO.

Letters Patent No. 74,291, dated February 11, 1868.

IMPROVEMENT IN RANGES.

The Schedule referred to in these Letters Patent and making part of the same.

TO ALL WHOM IT MAY CONCERN:

Be it known that I, D. K. Boswell, of Columbus, in the county of Franklin, and State of Ohio, have invented certain new and useful Improvements in Stoves; and I do hereby declare that the following is a full and complete description of the construction of the same, reference being had to the accompanying drawings, making a part of this specification, in which—

Figure 1 is a front view of the stove.

Figure 2 is a top view.

Figures 3, 4, and 5 are detached sections, to which reference will be made.

Like letters of reference refer to like parts in the views.

In fig. 1, A is the chimney or wall, in which the stove, B, is bricked up. This stove consists of the grate and fire-box C, the ash-pit D, immediately under the grate. D' are the front doors, one of which is shown as being opened. E is also a door above the grate, through which the stove is supplied with fuel. The fire-box is surrounded on the back and sides with a water-tight chamber, fig. 4, also, indicated by the dotted lines F, fig. 2, which is to be filled with water, and thus serve as a lining to the fireplace, instead of bricks, as in the ordinary stove. This lining or chamber is cast separately from the stove, and fitted to the same, and placed therein after the stove is put together; hence a new lining can be supplied when the old is burned out. This form of lining is much cheaper, and will last longer than an ordinary brick one, at the same time afford a constant supply of hot water for domestic use, which can be drawn off by appropriate cocks arranged for that purpose.

Immediately above the stove is an oven, G, which is constructed of sheet tin or iron, and so arranged that it can be taken out or removed from the top of the stove, and thereby give free access to the stove for cooking or other purposes. Fig. 3 represents the oven removed. It will be observed that the oven is divided into two sections, by a partition-plate, H, fig. 3, also indicated by the dotted line H'. The fire-box is also shown as being divided in the same direction by a plate, I, fig. 4, also indicated by the dotted line I', and shown detached in fig. 5; the two plates being in the same right line dividing the oven and fire-box equally, the purpose of which is, that when a small amount of fire is needed, one half of the fireplace can be used in connection with one half of the oven, and thus economize the consumption of fuel, and also prevent heating the room in warm weather. The whole space of the fire-box and oven, however, can be used at once, by simply removing the division-plates, which is easily and quickly done.

This arrangement of the stove is simple and convenient, and, when used for cooking, by closing the doors D', one of which is shown as being open, all the smoke, steam, and odor arising from the cooking food are carried off directly into the chimney, or through the flues J, which may be so arranged for that purpose, thereby leaving the room free from steam and odors.

What I claim as my improvement, and desire to secure by Letters Patent, is—

The herein-described stove, either bricked up in a chimney, or standing out in a room, provided with a portable or movable oven, G, water-lining F, and division-plates H I, all arranged in the manner as and for the purpose substantially as set forth.

D. K. BOSWELL.
